ATTORNEY

UNITED STATES PATENT OFFICE.

SIMON WEISS, OF ALLENTON, WISCONSIN.

MILK-CAN CLOSURE.

1,301,205.

Specification of Letters Patent. Patented Apr. 22, 1919.

Application filed March 13, 1916. Serial No. 83,700.

To all whom it may concern:

Be it known that I, SIMON WEISS, a citizen of United States, and resident of Allenton, in the county of Washington and State 5 of Wisconsin, have invented new and useful Improvements in Milk-Can Closures, of which the following is a description, reference being had to the accompanying drawings, which are a part of this specification.

10 This invention has for its object to provide a closure for milk cans and the like which will form a tight sealing connection between the cover and the can neck that will neither permit of the milk being spilled 15 therefrom nor allow dust to enter the can.

Cans of milk are commonly left standing on loading platforms at the roadside and at railway stations, and on windy, dusty days the dust is blown through the loose fitting 20 joint between the flanged cap and the can neck, thus contaminating the contents. The present invention provides an air tight sealing closure for the milk can which will be 25 free from this objection.

With the above and other objects in view the invention consists in the milk can closure as herein claimed and all equivalents.

Referring to the accompanying drawing, in which like characters of reference indicate 30 the same parts in the different views,

Figure 1 is a side elevation of a milk can closure constructed in accordance with this invention;

Fig. 2 is a sectional view thereof;

35 Fig. 3 is a plan view of a portion of the cover inverted, showing one of the clamping hooks thereof;

Fig. 4 is a plan view of a portion of the neck of the can showing the cam flange 40 thereof; and,

Fig. 5 is an enlarged detail view of the sealing connection.

In these drawings 10 indicates the neck portion of a milk can which is provided 45 with a heavy reinforcing metal band 11 around its edge, said band having its upper edge rounded to form a part of the sealing closure as will be later described. The cover member 12 has a horizontal shoulder portion

50 13 around its edge and a downwardly extending vertical annular flange 14 neatly fitting around the ring 11. In the right angular rabbet formed between the horizontal portion 13 and the surrounding flange 14 on 55 the inside of the cover is seated a rubber

strip 15 which is approximately square in cross section and is of sufficient length to fit entirely around the inside of the cover where it is held in place by a metal ring 16 of sufficient diameter to crowd the rubber 60 strip between it and the flange 14.

At diametrically opposite points the metal ring 11 of the can neck has angle strips 17 secured thereto in an inclined position, while the flange 14 of the cover at corresponding 65 points has hook-shaped lugs 18 secured to it, the inturned hook ends of the lugs 18 serving to engage the outturned inclined flanges of the angle strips 17 in the manner shown in Figs. 1 and 2. The inclination 70 given to the angle strips 17 is in the same rotary direction so that when the cover is placed on the can neck and is given a turn both of the hooks 18 engage the flanges 17 and are drawn downwardly thereby, the inclined flanges acting as cams to embed the rounded upper edge of the ring 11 into the rubber gasket 15 in the manner shown in Fig. 5.

The double cam action in tightening the 80 sealing connection between the can neck and its cover assures an air tight fit entirely around the cover that will not permit of dust or water entering the can and will therefore serve to protect the contents of the 85 can from contamination. At the same time the rubber gasket is so arranged that it may be readily removed for cleaning, it being only necessary to withdraw the ring 16 from within the gasket, thus relieving the pressure 90 on the gasket and permitting it to be withdrawn. When the parts have been washed they may be quickly fitted together for use. The ring 16 is preferably made of spring metal which will permit it to readily 95 resume its normal shape after being bent, thus permitting it to be more readily removed by merely bending it from its truly circular shape and also permitting it to spring back into clamping engagement with 100 the rubber strip when the parts are reassembled.

What I claim as new and desire to secure by Letters Patent is:

A milk can closure, comprising a cover 105 provided at its edge with a horizontal portion and a vertical flange extending downwardly therefrom to form therewith an internal annular rabbet, a strip of yielding material seated in the rabbet and forming a 110

gasket, an expanding ring of spring metal bearing with pressure against the inner edges of the gasket, a can neck having a rounded upper edge bearing against the gasket between the flange and the ring, and means for drawing the cover and can neck together.

In testimony whereof, I affix my signature, in presence of two witnesses.

SIMON WEISS.
